Specification for Design.

Patented July 13, 1920.

Application filed March 26, 1920. Serial No. 369,111. Term of patent 7 years.

To all whom it may concern:

Be it known that I, ALFRED D. E. SESSIONS, a citizen of the United States of America, residing at Red Wing, in the county of Goodhue and State of Minnesota, have invented a new, original, and ornamental Design for a Hairpin, of which the following is a specification, reference being had to the accompanying drawing, forming part thereof.

In the drawing:

Figure 1 is a view in elevation showing my new design for hair pins;

Fig. 2 is an edge elevation thereof.

I claim:—

The ornamental design for a hairpin as shown.

ALFRED D. E. SESSIONS. [L. S.]
